VARIABLE DISPLACEMENT PUMP CONTROL
MECHANISM

Leslie B. M. Buchanan, Springfield, Mass., assignor to Westinghouse Electric Corporation, East Pittsburgh, Pa., a corporation of Pennsylvania

Application July 27, 1945, Serial No. 607,459

2 Claims. (Cl. 103—38)

1

This invention relates generally to control means and more particularly to control means for variable displacement hydraulic pumps.

Although the present invention has various applications, it is particularly adapted for use in controlling the traversing of the gun turret of a military tank by means of a hydraulic power transmission incorporating a variable displacement pump. One type of variable displacement pump commonly used in such installations has a slide block which is movable to vary the displacement of the pump. Movement of the slide block of the pump has heretofore been controlled by means of a hydraulically operated cam mounted in the pump casing in combination with a complicated system of mechanical servo linkage arranged to equalize the operation of a hydraulic control valve and to stop the cam, and therefore the slide block, in the desired position. Because of the hydraulic and mechanical connections used with this construction it has been necessary to locate the controls to be actuated by the operator in a position immediately adjacent the pump. This necessitates placing the entire pump and hydraulic mechanism in the fighting compartment of the tank turret. Since the available space in the fighting compartment of a tank turret is extremely limited, it would obviously be very desirable to be able to control the variable displacement pump by remote control means so that the pump and the hydraulic control means could be divorced from the operator's control handle and located in a remote and more spacious portion of the tank, such as in the hull thereof, with only the operator's control handle remaining in the fighting compartment adjacent the operator's position.

It is therefore a primary object of the present invention to provide control means for a variable displacement pump permitting the latter to be remotely operated by means of a small compact actuating unit, and enabling the bulky pump mechanism and hydraulic controls to be located remotely from the operator's position. With the present invention, the remote control means comprises electrical controls which are simple in character and which may readily be connected to the pump and its hydraulically operated control means whether the latter be located in the turret of the tank or in the hull thereof.

A further object of the present invention is to provide control means for a variable displacement pump in which the reaction pressure generated by the pump, when the slide block is displaced from concentric relation with respect to

2

the drive shaft of the pump, is counter-balanced at all times, and does not interfere with the accuracy of the control of the pump.

Other objects and advantages of the present invention will be made more apparent as this description proceeds, particularly when considered in connection with the accompanying drawings, in which:

Figure 1 is an elevation, partly in section, of a portion of the gun turret of a tank;

Figure 2 is a semi-diagrammatical cross-sectional view of the variable displacement pump, hydraulic motor, and control means for traversing the gun.

15 Referring now to the drawing, and particularly to Figure 1, the reference character 10 indicates the top of the hull of a military combat tank having a turret opening 11 in which is fitted and secured the usual bearing race 12 for the turret. 20 The turret is designated by the numeral 13 and carries a gun 14, mounted upon trunnions 15 for adjustment in elevation. The turret 13 carries a complementary bearing race 16 in the form of a base ring. A set of bearings 17 is inserted between the two races. The lower and inner edge of the race 12 is formed as an internal ring gear 18 for a purpose which will be presently described.

25 Mounted upon the turret of the tank is a constant displacement traverse motor 19 which is adapted to be actuated by means of a variable displacement pump in the manner to be herein-after described. The motor 19 operates through suitable gearing in the housing 20 to drive a pinion 21 meshing with the internal ring gear 18 fixed on the hull of the tank. The gearing in the housing 20 adapted to drive the pinion 21 is arranged to be selectively coupled either to the traverse motor 19 or to the manual traverse crank 40 22' by means of a clutch (not shown) operated by the handle 22. With this construction the turret is normally traversed by means of the traverse motor, but in the event of failure of the hydraulic power traversing mechanism, may be manually traversed by manipulation of the crank 22' by 45 the operator.

Referring now to Figure 2, the constant displacement traverse motor 19 is adapted to be actuated by means of the variable displacement pump 23, which in turn is controlled by the electro magnetic valve 24. The motor 19 is provided with a rotating cylinder 25, formed integrally with a drive shaft (not shown), the latter being connected through suitable gearing to the pinion 21 meshing with the large internal ring

gear 18. The cylinder 25 has a plurality of generally radially extending bores 26 in which are mounted small pistons 27. At their radially inner ends the bores 26 are adapted to communicate with ports 28 and 29 provided in the stationary flat valve 30. The ports 28 and 29 are crescent-shaped and the upper port 28 is adapted to communicate with the bores 26 of the cylinder as they pass through the arc of the upper port, whereas the lower port 29 is adapted to communicate with the bores as they pass through the arc of that port.

The roller bearing race 31 is rotatably mounted in the motor case 32 upon roller bearings 33. The roller bearing race 31 and the cylinder 25 are mounted in the motor case 32 at a fixed eccentricity with respect to each other to provide piston stroke.

Counter-clockwise rotation of the cylinder 25 and its driveshaft is accomplished when oil under pressure is furnished by the pump 23 through the conduit 34 to the upper port 28 of the flat valve 30. Port 28 communicates with the bores 26 to force the pistons 27 passing through the adjacent arc of the port outwardly, causing the race 31, cylinder 25 and drive shaft of the motor to be rotated in a counter-clockwise direction. Simultaneously, the pistons 27 passing through the arc of the lower port 29 discharge oil through the port 29 to the conduit 35 which returns the oil to the pump 23. The pistons 27 are maintained in contact with the roller bearing race 31 by centrifugal force plus hydraulic pressure.

The variable displacement pump 23 comprises a cylinder 36 formed integrally with an drive shaft (not shown) which is driven by a suitable electric motor. The cylinder 36 is provided with a plurality of generally radially extending bores 37 in which are mounted a plurality of pistons 38. The pistons 38 are reciprocable in the cylinders and are urged by centrifugal force into engagement with a roller bearing race 39 rotatably mounted in a slide block 40 by means of roller bearings 41. The slide block 40 is mounted for sliding movement or reciprocation within the pump casing 42 upon ways provided in the casing. Ball bearings 44 are positioned between the ways 43 and the slide block 40.

The bores 37 and the cylinder 36 are adapted to communicate at their radially inner ends with ports 45 and 46 provided in a stationary flat valve 47.

When the slide block 40 is positioned in concentric relation with the cylinder 36, as shown in Figure 2, there is no reciprocation of the pistons 38 as the cylinder rotates, and consequently no oil is delivered by the pump. Displacement of the slide block 40 from its concentric relation with the cylinder and drive shaft to a position eccentric thereto results in reciprocation of the pistons 38 as the integral drive shaft and cylinder 36 rotates.

When the slide block 40 is displaced to the left from the neutral position shown in Figure 2, assuming the drive shaft and cylinder to be rotated in a counter-clock-wise direction by the motor, the reciprocating pistons 38 deliver oil under pressure to the lower port 46 of the flat valve 47 as they pass through the arc of that port. The oil under pressure is delivered from the port 46 through the conduit 34 to the motor 19, effecting a rotation of the cylinder and drive shaft of the motor in the manner hereinbefore described. At the same time, exhaust oil from the motor 19 is returned through the conduit 35

to the port 45 of the flat valve 47 and is delivered to the bores 37 in the cylinder 36, as they pass through the arc of the port 45.

Although a closed fluid system is thus provided between the motor 19 and the pump 23, there is provided a hydraulic reservoir 48 and a motor-driven gear pump 49 to maintain the system completely filled with oil and to replace any leakage therefrom.

The mechanism hereinabove described is well known in the art and is used in turret traversing mechanisms installed in combat tanks.

The present invention consists essentially in the control means for varying the position of the slide block of the variable displacement pumps, as hereinafter described.

Mounted in the pump casing 42 is a cylinder 50 having a piston 51 reciprocable therein. The piston 51 is provided with a piston rod 52 having its forward end connected to the slide block 40. The end of the piston rod 52 is threaded and adjustably engages the slide block 40. A suitable lock-nut 53 is provided to lock the slide block and connecting rod in the adjusted position. Coil springs 54 and 55 are provided in the cylinder 50 on opposite sides of the piston 51, and function to maintain the piston centered in the cylinder when there is no pressure differential in the cylinder on opposite sides of the piston. The springs 54 and 55 may be preloaded, or compressed, when assembled in the cylinder. When the piston 51 is thus centered, the slide block 40 is positioned in concentric relation with the cylinder 36 of the pump.

It will be apparent that the application of fluid pressure on one side of the piston 51 is effective to vary the position of the slide block 40 and consequently to vary the eccentricity thereof with respect to the cylinder 36. As the aforementioned eccentricity increases, the volume of oil delivered by the variable displacement pump 23 is increased proportionately since the stroke of the pistons 38 is greater. In a like manner the speed of the motor 19 is dependent upon the volume of oil delivered by the pump. Reversing the eccentricity of the slide-block 40 with respect to the cylinder 36 reverses the flow of oil through the pump and results in reversing the direction of rotation of the motor 19. Thus it will be seen that the speed of the motor 19, and accordingly the speed of rotation of the turret 13 in either direction, is accurately controlled by varying the position of the slide block 40 by means of the application of fluid pressure in the cylinder 50.

24 is an electro-magnetic valve arranged to control the flow of fluid through the conduits 56 and 57 to the cylinder 50 on opposite sides of the piston 51. The electro-magnetic valve 24 may be built as part of the pump 23, or may be a separate unit connected to the pump by the conduits 56 and 57, as shown. The motor driven gear pump 58 provides fluid under pressure to the conduits 56 and 57. By-pass conduits 59 and 60 establish communication between the conduits 56 and 57 and the fluid pressure valves 61 and 62 respectively. The valves 61 and 62 have exhaust ports respectively controlled by plungers 63 and 64. These plungers are arranged to be reciprocated by the magnet bar 65 which is pivoted intermediate its end upon the fulcrum 66. Magnet coils 67 and 68 are wound upon cores 69 and 70 respectively and are adapted to be energized to pivot the magnet bar 65 about the fulcrum 66, thus moving the plungers 63 and 64 to open one

of the pressure valves and simultaneously close the other.

One end of each coil 67 and 68 is grounded at 71 and the opposite ends are connected to the center terminals of a double-pole, double-throw switch 13. The switch is adapted to connect the coils to either of two potentiometers 74 and 75. The potentiometers 74 and 75 are provided with manual controls 16 and 77, which may be operated to vary the electrical power supplied to the coils 67 and 68 from the power source 78.

It will be seen that operation of the potentiometers connected by the switch 13 to the magnet coils 67 and 68 increases the energy supplied to one coil and simultaneously decreases that supplied to the other, resulting in rocking the magnet bar 65 about its fulcrum 60. In this manner, one of the plungers 63 and 64 is moved toward its adjacent pressure valve and restricts the port or orifice thereof while the other plunger moves away from its adjacent pressure valve and opens the orifice thereof. The orifices of the pressure valves 61 and 62 provide in effect means for bypassing the fluid supplied to the conduits 56 and 57 from the gear pump 58, and regulation of the size of the orifices by the plungers 63 and 64 results in increasing the pressure to one side of the piston 51 in the cylinder 50 and simultaneously decreasing the pressure supplied to the opposite side of the piston. In this manner controlled reciprocation of the piston 51 and the slide block 40 connected thereto is secured.

The springs 54 and 55 in the cylinder 50 on opposite sides of the piston 51 oppose movement of the piston by the differential pressure in the conduits 56 and 57 and function to measure the movement of the pistons and to control the movement thereof in accordance with the amount of power supplied at the potentiometers. In other words, a definite position of the piston 51 and accordingly the slide block 40 is obtained for each given pressure differential between the conduits 56 and 57.

With the present construction, the electro-magnetic valve 24 and the variable displacement pump 23 can be remotely controlled by means of the potentiometers 74 and 75 which are connected to the electro-magnetic valve only by means of a pair of conductors. Accordingly, the pump and electro-magnetic valve may be positioned in any suitable location in the tank, and the controlling potentiometers may be located in the fighting compartment of the tank turret adjacent the operator's position. Since the potentiometer controls are small and compact it is apparent that they occupy little space and may be conveniently located in the turret. On the other hand, pump and electro-magnetic valve are relatively large and when located in the limited space provided in the fighting compartment of the tank turret are in the way and impair the efficiency and free movement of the personnel stationed therein. Furthermore they obstruct the efficient location and arrangement of other apparatus in the turret. By remotely locating the traversing mechanism from the controls, a more efficient interior arrangement of the tank is possible.

The use of two potentiometers 74 and 75, as shown in Figure 2, enables the traversing mechanism to be controlled by either of two operators at two separate stations, simply by operating the switch 13 to connect the magnet coils 67 and 68 to the potentiometer at the desired station. If desired, of course, only one potentiometer is nec-

essary if the traversing mechanism is to be controlled and operated from a single station.

An inherent characteristic of variable displacement pumps of the type illustrated and described is that movement of the slide block to an eccentric position with respect to the cylinder and drive shaft thereof produces a reaction force within the pump, tending to return the slide block to concentric relation with the cylinder and drive shaft. In the construction shown in Figure 2, means are provided for counter-balancing this reaction pressure generated by the pump so that it will not interfere with the accurate operation of the traversing mechanism. A cylinder 80 is provided as an extension of the cylinder 50 and receives a piston 81 mounted for reciprocation therein. The piston 81 in the cylinder 80 is connected to the piston 51 in the cylinder 50 by means of the connecting rod 82, for reciprocation therewith as a unit. A guide rod 83 of the same diameter as the connecting rod 82, extends from the opposite side of the piston 81 and is received in a guide bore 84 provided in an extension 85 of the cylinder 80. The conduit 34 from the variable displacement pump 23 communicates with the cylinder 80 on one side of the piston 81 by means of the conduit 86, and the conduit 35 from the pump communicates with the cylinder 80 on the opposite side of the piston 81 by means of the conduit 87. The piston 81 is of such diameter that the reaction force of the variable displacement pump 23 tending to return the slide block to concentric relation with the drive shaft is counterbalanced by the output oil pressure from the pump acting upon the piston 81. For example, displacement of the slide block 40 to the left from the position shown in Figure 2 results in a reaction force in the pump, tending to move the slide block to the right and to reduce its displacement from its concentric relation with respect to the drive shaft and cylinder. With the slide block displaced to the left oil flows through the conduit 34 to the motor 19 and is also supplied to the right side of the piston 81 by means of a conduit 86. In this manner the output oil pressure from the pump tends to move the small piston 81 to the left, and inasmuch as this piston is connected by the connecting rod 82, piston 51 and connecting rod 52 to the slide block 40, it will be apparent that the reaction force tending to move the slide block to the right is counterbalanced. The reaction force generated in the pump when the slide-block is displaced to the right from its position shown in Figure 2, is similarly counter-balanced by means of the output oil pressure from the conduit 35 being applied on the left side of the piston 81 through the conduit 87, thus counter-balancing a reaction pressure in the pump.

Since the reaction pressure in the pump tending to return the slide block to its neutral position is a function of the output pressure, the reaction force will be increased as the displacement is increased and as the output pressure is increased. Since, however, the output pressure acts directly upon the piston 81, the reaction pressure in the pump is always counter-balanced by the small piston 81. Accordingly, when an increase is required in the torque necessary to rotate the turret, the pump output pressure is increased, but the increased reaction force in the pump is counter-balanced by the increased counter-balancing force of the piston 81.

Although I have shown and described certain embodiments of the invention, it will be under-

stood that I do not wish to be limited to the exact construction shown and described, but that various changes and modifications may be made without departing from the spirit and scope of my invention, as provided in the appended claims.

What I claim is:

1. In a closed fluid power transmission system of the character described wherein a pair of fluid conduits for delivery and return fluid flow are connected to respective ports of a variable displacement hydraulic pump having a slide block which is movable to vary displacement of the pump, pump displacement control mechanism comprising, in combination, a pair of cylinders arranged together in tandem, a pair of pistons rigidly connected to each other and movable as a unit within said cylinders, each of said pair of pistons being within a respective one of said pair of cylinders, means rigidly connecting said connected pair of pistons to said slide block for unitary movement with the latter, means establishing fluid communication between said pair of fluid conduits and one of said cylinders at respective opposite sides of the one of said pistons therein, whereby reaction force of said slide block during operation of said pump is counterbalanced by fluid pressure acting on said one of said pistons, a source of fluid pressure, a pair of fluid pressure conduits connecting said source of fluid pressure to the other of said cylinders at respective opposite sides of the said piston therein, a pair of valves for selectively regulating fluid pressure in respective ones of said pair of fluid pressure conduits, electro-magnetic means for controlling said pair of valves, and manually operable electric control means for variably regulating said electro-magnetic means.
2. In a closed fluid power transmission system of the character described wherein a pair of fluid conduits for reversible delivery and return fluid flow are connected to respective ports of a variable displacement hydraulic pump having

a slide block which is movable to vary displacement of the pump, pump displacement control mechanism comprising, in combination, a pair of abutting cylinders arranged with their horizontal axes in alignment, a piston in each of said cylinders, a connecting rod rigidly connecting the piston in one of said cylinders to the piston in the other of said cylinders, a rod rigidly connecting said connected pistons and said connecting rod to said slide block for movement as a unit with the latter, a pair of connections establishing fluid communication between said pair of fluid conduits and one of said cylinders at respective opposite sides of said piston therein, whereby reaction force of said slide block during operation of said pump is counter-balanced by fluid pressure acting on said piston in said one of said cylinders, a source of fluid pressure, a pair of connecting conduits establishing fluid communication between said source of fluid pressure and the other of said cylinders at respective opposite sides of said piston therein, a pair of valves for selectively regulating fluid pressure in respective ones of said pair of connecting conduits, and manually operable electric control means for variably regulating operation of said valves.
